UNITED STATES PATENT OFFICE.

EDGAR A. GILLINDER, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA.

DESIGN FOR A GLASS SHADE FOR ELECTRIC-LIGHT FIXTURES.

Application filed July 1, 1925. Serial No. 13,966. Term of patent 3½ years.

To all whom it may concern:

Be it known that I, EDGAR A. GILLINDER, a citizen of the United States, residing in the city and county of Philadelphia, State of Pennsylvania, have invented a new, original, and ornamental Design for Glass Shades for Electric-Light Fixtures, of which the following is a specification, reference being had to the accompanying drawing, forming part thereof.

Figure 1 is a side elevation of my novel ornamental shade.

Figure 2 is a top plan view of one-half of my novel ornamental shade. Figure 3 is a vertical section on line 3—3 of Figure 1.

I claim:—

The ornamental design for a glass shade for electric-light fixtures, as shown.

EDGAR A. GILLINDER.
